SNAP HOOK

Joseph T. Rebotsky, Los Angeles, Calif., assignor
of one-half to Farrel W. Snellings, Compton,
Calif.

Application November 17, 1949, Serial No. 127,911

1 Claim. (Cl. 24—237)

1

The present invention relates to fasteners and catches of the so-called snap hook variety and has reference to a style, generally well known, which is characterized by a pair of opposed complementary hooks having bill portions which are situated in opposite positions to provide accessible and registerable mouth portions to seat and hold a connecting ring or link carried by a chain or equivalent element.

An object of the invention is to structurally, functionally and otherwise improve on double-type snap hooks and, in so doing, to provide a distinctly different kind of fastener in which manufacturers and users will find their respective requirements and needs more satisfactorily met, contained and expeditiously available.

Another object of the invention is to provide a fastener of the class under consideration which lends itself to practical production from various kinds of metals such as gold, silver, platinum, steel, brass, commercial plastics and the like.

A further object is to provide a twin-hooks snap fastener which may be used to great advantage in conjunction with jewelry such as earrings, watch chains, necklaces, bracelets, anklets and the like.

A still further object is to provide a fastener which, constructed as herein shown and described, may be aptly used in connection with fishing tackle, may be used aptly on wearing apparel, bridle harnesses, dog leashes, electrical fixtures and whatnot.

In addition to strength, durability and simplicity, the fastener is expressly designed in a manner which will enable it to be advantageously employed in that a ring or link on a chain or other element may be hooked and unhooked by the sense of touch and without having to resort to the sense of vision, making it ideal for adoption and use by persons having poor eye sight, and for use in connection with countless articles of jewelry.

More specifically, novelty is predicated upon a fastener having an eye at one end, with or without a swivel, and complementary twin hooks at the opposite end, said hooks being resilient and the respective bill and mouth portions being substantially closed, whereby to provide normally closed hooking-eyes of great strength and reliability.

What is more, it is a cardinal purpose to provide a twin-hooks fastener with substantially closed hooks and with laterally flared terminals on the bill portions these coinciding and registering with a link receiving and guiding loop which

2

mechanically regulates the inserting and removing positions of the chain link so that it is self-guided into and out of position in respect to said hooks and so that the usual quarter-turns in clockwise and counter clockwise directions are virtually governed by an expansible and contractible crotch forming an end portion of said loop.

Other objects and advantages will become more readily apparent from the following description and the accompanying illustrative drawing.

In the accompanying sheet of drawings, wherein like numerals are employed to designate like parts throughout the views:

Fig. 1 is a perspective view which shows in dotted and full lines a twin-hooks fastener at the left and a link at the right, the link being shown in its several stages of insertion between the hooks;

Fig. 2 is a perspective view based on Fig. 1 and showing the final step, that is, after the link has been passed into the loop, turned 90° from left to right and pulled back and anchored in the hooks;

Fig. 3 is an edge elevation; and

Fig. 4 is a side elevation at right angles to and observing Fig. 3 in a direction of right to left.

Referring now to the drawings by reference numerals and accompanying lead lines the fastener unit or snap hook is denoted, as a unit, by the numeral 6 and the chain unit, which is adapted to be releasably connected thereto, is denoted by the numeral 8. In the latter, the numeral 10 may designate a chain, rod, or other element provided with a flat elongated coupling link 12. Obviously, the link 12 may be a ring or of any other geometrical shape. The invention primarily resides in the fastener or unit 6 but is to be interpreted with and without the unit 8.

Unit 6 is here shown as formed from a single length of metal or suitable material bent upon itself to provide limbs having an eye 14 at one end and complementary hooks 16 and 18 at the opposite ends. These hooks, instead of being partly or wholly open, as is generally the case with snap hooks of this class, are substantially closed. That is to say, the respective mouth portions of the hooks are closed and instead of calling them "hooks" they could be perhaps referred to as openable and closable eyes with which link 12 is adapted to be releasably connected. Between its ends, the unit 6 has its limb portions fashioned into what may be conveniently referred to as a guide loop 20. This is an espe-

cially important part in that it is so made and its components are so angled and related to the hooks 16 and 18 that it is not only the loop, but, functionally, constitutes clearance means, guard means and guide means for the link. It follows that one reach or side member of the loop is set to the left of the longitudinal axis of the fastener and the other one offset to the right as brought out in the edge or top plan view seen in Fig. 3. The intermediate portions are bent and one bend 22 is to the left and the other bend 24 to the right. These bends define important converging guides 26 and 28 which, in turn, define an expandible and contractible V-shaped crotch. Attention is called at this time to the fact that the space 34 between the opposed parallel hooks 16 and 18 defines a straight-away passageway between the inner opposed surfaces of the two hooks. Since the bill portions of the hooks come in direct contact with the respective coacting limb portions, they define normally closed mouths. The mouth portions being on opposite sides of the passageway provide, in this manner, what is a common entrance and exit for the respective hooks. The expandible and contractible vertex of the V-shaped crotch merges into the passage and coincides therewith at the stated entrance and exit for said hooks.

It will be noted too that the substantially closed bill portions of the hooks are flared outwardly as at 30 and 32 (see Fig. 4). In all of these double or twin-type snap hooks, the bill portions open in diametrically opposite directions and therefore this principle of construction is quite old. It is thought to be new, however, to have the laterally flared bill portions forming substantially closed mouths and with said bill portions coinciding with a crotch defined by the guides 26 and 28, which crotch smoothly "feeds" the link into the hooks. Then, too, by having the guides thus converging and offset to opposite sides of the longitudinal axis of the fastener in the unit, they are properly located to govern and direct the quarter-turn step of operation of the link. It is customary in these types of fasteners that when the link or ring is passed between the hooks for fastening, it is given a turn in either one direction or the other and then pulled out again and lodged in the seating portions of the hooks. In this arrangement when the link is inserted and passed between the hooks by way of the passageway or space 34 (see Fig. 1) it is moved in the direction of the arrows (A) and is pressed into the V-crotch of loop means 20. Here it has clearance for the necessary quarter-turn. It will be noted, however, that it cannot be turned in a counter clockwise direction and therefore its natural incline leans in the proper clockwise direction. Therefore, the link is virtually self-turning, as it were, and feeds and guides itself by way of the guides 26 through the openable mouths and into the seat portions of the hooks 16 and 18. This will be clear by comparing the first step of moving the link in the direction of arrows (A) in Fig. 1 and the second step of moving the links in the direction of arrows (B) in Fig. 2. The tips of the terminals of the respective hooks are in a coinciding plane with each other and line up and coact with the guides 26 and 28 in rendering the insertion and removal

steps substantially positive and foolproof. To unhook the link, all that is required is to snap same past the ends of the hooks and give a quarter-turn and the link is completely disengaged from the hooks. Due to the construction shown there is no chance of the link slipping into connection with one hook only. Almost invariably, the link is simultaneously seated in both hooks. The engaging step is quite as simple and smooth. By having the substantially closed hooks or "eyes" 16 and 18 a much stronger construction is had to withstand pressure and wear and tear.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Having described the invention, what is claimed as new is:

A chain link fastener of the class described comprising a snap hook unit embodying a pair of individual resilient limbs connected with one another at corresponding ends, the opposite corresponding ends of said limbs being disconnected, free, and flexibly movable toward and from one another, said limbs being completely situated one on each side of the exact longitudinal center line of said unit, an intermediate portion of one limb being in substantial parallelism and bent laterally outward and then laterally inward, the latter bend defining a guide, the free end of said limb being looped upon itself and defining a hook, the bill portion of said hook being in resilient contact with said guide and providing an openable and closable throat, the remaining limb being bent laterally outward and then laterally inward, the latter bend defining a second guide, the free end portion of said remaining limb being looped upon itself in a direction opposite to said first-named looped portion and defining a second hook, the bill portion of the latter hook being in resilient contact with the corresponding guide and providing a second openable and closable throat, the respective throats being in opposed alignment with each other and defining a common unobstructed expandible and contractible link entrance for said hooks, said hooks defining an expandible and contractible link accommodating passageway between themselves, said guides being disposed in non-crossing side-by-side relationship and converging toward said common entrance and said passageway and defining a V-shaped crotch whose vertex is expandible and contractible and is in communicative registration with said common entrance.
